(57) **CLAIM**

The ornamental design for a display screen with graphical user interface of a gaming machine as shown and described.

DESCRIPTION

The FIGURE is a front view of a display screen with graphical user interface of a gaming machine showing our new design.

The display screen is shown with a symbolic break in length. The appearance of any portion of the display screen between the break lines indicated by brackets forms no part of the claimed design. The broken lines depicting the remainder of the display screen with graphical user interface of a gaming machine form no part of the claimed design.
